[57] **CLAIM**

The ornamental design for a jewelry component, as shown and herein described.

DESCRIPTION

FIG. 1 is a perspective view of a first embodiment of my jewelry component shown in a position of use, the broken line showing of the adjoining components is for illustrative purposes only and forms no part of the claimed design; FIG. 2 is a perspective view;

FIG. 3 is a top plan view;

FIG. 4 is a side elevational view, of which the opposite view is a mirror image;

FIG. 5 is a perspective view of my a jewelry component showing a second embodiment of my a new design;

FIG. 6 is a side elevational view, of which the opposite view is a mirror image;

FIG. 7 is a right side view of FIG. 5, of which the opposite view is a mirror image;

FIG. 8 is a perspective view of a third embodiment of my jewelry component shown in a position of use, the broken line showing of the adjoining components is for illustrative purposes only and forms no part of the claimed design;

FIG. 9 is a perspective view;

FIG. 10 is a top plan view;

FIG. 11 is a side elevational view, of which the opposite view is a mirror image;

FIG. 12 is a perspective view of my jewelry component showing a fourth embodiment of my a new design;

FIG. 13 is a side elevational view, of which the opposite view is a mirror image;

FIG. 14 is a right side view of FIG. 13, of which the opposite view is a mirror image;

FIG. 15 is a a perspective view of a fifth embodiment of my jewelry component shown in a position of use, the broken line showing of the adjoining components is for illustrative purposes only and forms no part of the claimed design;

FIG. 16 is a perspective view;

FIG. 17 is a top plan view;

FIG. 18 is a side elevational view, of which the opposite view is a mirror image;

FIG. 19 is a cross-sectional view of line 19—19 of FIG. 17;

FIG. 20 is a perspective view of my a jewelry component showing a sixth embodiment of my new design;

FIG. 21 is a side elevational view, of which the opposite view is a mirror image;

FIG. 22 is a right side view of FIG. 21, of which the opposite view is a mirror image;

FIG. 23 is a perspective view of my a jewelry component showing a seventh embodiment of my new design;

FIG. 24 is a side elevational view, of which the opposite view is a mirror image; and,

FIG. 25 is a right side view of FIG. 24, of which the opposite view is a mirror image.

The surface(s) or portion(s) of the article not shown in the drawing or described in the specification form(s) no part of the claimed design.
